ALBERT MARKS, OF NEW YORK, N. Y.

HAND STAMPING-MACHINE.

1,121,518.

Specification of Letters Patent. Patented Dec. 15, 1914.

Application filed August 31, 1912, Serial No. 718,096. Renewed September 2, 1914. Serial No. 859,918.

To all whom it may concern:

Be it known that I, ALBERT MARKS, a citizen of the United States, and a resident of the city of New York, borough of Brooklyn, in the county of Kings and State of New York, have invented a new and Improved Hand Stamping-Machine, of which the following is a full, clear, and exact description.

This invention relates to hand-stamping devices and has particular reference to a machine made principally of metal and having consequently a set of metallic type characters as distinguished from stamping devices having rubber characters.

Among the objects of this invention in addition to the provision of a metallic construction is to provide a device of a very simple and compact nature, whereby the trade may be supplied at a low cost with a machine which will meet all ordinary requirements.

The foregoing and other objects are attained in a preferred manner by the mechanism hereinafter described and claimed and illustrated in the accompanying drawings, in which—

Figure 1 is a side elevation of the machine partly broken away; Fig. 2 is a vertical section of the same; Fig. 3 is a vertical section 30 taken at right angles to Fig. 2; and Fig. 4 is a view corresponding to Fig. 2, but with the parts in the opposite position.

Throughout the following description and on the several figures of the drawings, similar parts are referred to by like reference characters.

Referring particularly to the drawings, I show at 10 a type cylinder of any approved construction, the several parts or characters 40 of which are made preferably of metal and journaled upon an axis 11 in a casing 12. The type mechanism may be of any desired construction and constitutes *per se* no part of the present invention. The casing 12 is provided with an upwardly extending stem 13 terminating in a handle 14 and is held normally elevated by virtue of a spring 15 operating between said handle and any suitable fixed abutment as at 13'. A shell or 50 housing 16 incloses the casing 12 and associated parts and extending upwardly therefrom is a sleeve 17 which incloses the stem 13 and spring 15, the upper end of the sleeve 55 projecting normally into a cavity 14' in the handle. The housing is shown as including a pair of side plates 18, which may be con-

nected to the main portion of the housing in any suitable manner or made integral therewith if desired. The lower ends of the side plates 18 are adapted to form the main support for the machine in the position indicated in Fig. 1 and each of said side plates is preferably provided with a central slot or opening 18'. The casing 12 carries a pair of screws or studs 19 which extend oppositely from each other therefrom and into said slots 18'. A pair of wings 20 are pivoted upon said studs 19 and extend downwardly substantially to the plane of the lower ends of the side plates 18. Each of 70 the wings 20 consists of an outer wall which is normally vertical, and extending at right angles to said wall, each of the wings has a pair of flanges 21 which lie just within the side plates 18. The lower edges 21' of 75 the said flanges are cam-shaped or curved, whereby when downward pressure is applied to the handle 14, the cams 21' will slide along the paper or material to be stamped, the wings separating as indicated in Fig. 4 80 of the drawings, the wings thereby being thrust out of the path of the cylinder 10 which is brought down at the same movement. The wings are provided at their upper portions with shoulders 22, which when 85 the parts are restored to normal position through the force of the spring 15, will co-operate with cams 23, formed on the shell 16 just within the side plates 18 and closely adjacent the studs 19. The effect of the 90 cams 23 is to cause the wings 20 to approach each other bringing them into the normal position indicated in Fig. 2, in which position they serve to substantially inclose the 95 type cylinder.

As a convenient means to effectively make the machine self-inking and to supply a fresh supply of ink to the type after each operation of the machine, I provide an ink pad 24 carried in a cradle 25. The cradle is 100 made preferably of sheet metal and is pivoted on the inside of one of the wings 20 by means of a pivot 26 extending through the flanges 21 of said wing and through a pair of downwardly-extending ears 25'. The 105 cradle constitutes in effect a bell crank, the longer arm of which overlaps the active type of the cylinder as indicated at 27, and the shorter arm of which in the normal position or while the device is approaching the normal position, co-operates with a pair of shoulders 28 adjacent the lower corners on 110

one side of the casing 12. When the wings are being restored to their normal position, the short arm of the cradle will ride up along said cams 28, which will result in 5 swinging the cradle, so that the end 27 thereof will come into contact with the active type characters. When the cylinder is operated downwardly, the cradle will swing downwardly and glide along the paper as 10 indicated in dotted lines in Fig. 2, the longer end of the cradle also gliding along the paper when the machine is undergoing the return or rebounding movement, so that the shorter arm of the bell crank will be made 15 to coöperate with the cams 28.

It will be understood that the self-inking mechanism herein set forth may be applicable to any type or design of hand stamping machine such, for instance, as dating machines, consecutive numbering machines or 20 the like, and for this reason I would have it understood that I do not wish to be limited in its use or application to a dating machine such as illustrated.

25 The several parts of the invention may be made of any suitable materials and the relative sizes or proportions thereof may be varied to a considerable extent, without departing from the invention hereinafter 30 claimed.

Having thus described my invention, I claim as new and desire to secure by Letters Patent:—

1. The herein described stamping machine, comprising a casing, a type cylinder carried within said casing, a shell, means to operate the casing in relation to the shell, a pair of wings pivoted to the casing and having cam-shaped lower ends for coöperation 35 with the article being stamped, an ink pad carried by one of the wings and a set of cams carried by the shell, serving to restore the wings to normal position with the ink pad in contact with the active type characters.

2. In a stamping machine, the combination of a casing, a type cylinder within the casing, movable downwardly therewith, a shell embracing the casing, a handle operative through said shell and connected with the casing, whereby the casing is operated downwardly and then upwardly, a pair of wings pivoted to the casing and adapted to separate at their lower ends by contact with 50 the paper being stamped when the casing is thrust downwardly, an ink pad carried by one of the wings, and means coöoperating with the ink pad to cause one portion of it to contact with the active characters on the 55 cylinder when the casing and wings are restored to normal position.

3. In a stamping machine, the combination of a stationary shell, a casing movable vertically in said shell, adjustable type mechanism carried by the casing adapted to be thrust downwardly into the plane of the lower end of the shell, means to restore the casing to normal elevated position, a wing pivoted to the casing and adapted to be thrown laterally out of the path of the type mechanism by contact with the paper being stamped when the casing is thrust downwardly, means to automatically restore the wing to normal position when the casing is returned to its elevated position, an ink pad carried by said wing, the ink pad comprising a bell crank structure, one portion of which is adapted to contact the active type characters for automatically re-inking the same and another portion of the bell crank being adapted to engage with the casing to cause said contact between the ink pad and the type characters.

4. In a stamping machine, the combination of a shell, type mechanism within the shell, means to force the type mechanism downward, an ink pad movable with the type mechanism relatively to the shell, cam mechanism coöperating with the paper being stamped to cause the ink pad to swing laterally out of the path of the type mechanism on the down stroke, and other cam mechanism to swing the ink pad back into contact with the type mechanism on the return stroke.

5. In a stamping machine, the combination of a casing, type mechanism carried by the casing, an ink pad normally in contact with the type mechanism and directly below the same, means to operate the type mechanism downwardly, and cam mechanism associated with the inking mechanism and co-operating with the paper being stamped to throw the same laterally out of the path of the type mechanism when the latter is operated.

6. In a stamping machine, the combination of a depressible casing, type mechanism carried by said casing, a wing freely pivoted upon said casing, and an inking pad freely pivoted upon said wing, said wing and pad being automatically moved from beneath the type mechanism by contact with the paper being stamped when the casing is depressed.

In testimony whereof I have signed my name to this specification in the presence of two subscribing witnesses.

ALBERT MARKS.
